UNITED STATES PATENT OFFICE.

BENJAMIN WOODHOUSE, OF SEATTLE, WASHINGTON.

PLASTER BOARD.

Application filed August 22, 1924. Serial No. 733,521.

To all whom it may concern:

Be it known that I, BENJAMIN WOODHOUSE, a citizen of the United States, and a resident of Seattle, King County, Washington, have invented certain new and useful Improvements in Plaster Board, of which the following is a specification.

This invention relates to improvements in plaster board and similar sheets of plastic composition such as may be used in building construction in lieu of the usual lath and plaster, or outside cement or stucco finish; more particularly the invention relates to the reinforcing of sheets of plaster board, 10 or the like, so as to prevent chipping, cracking, or breaking before and after being put into use.

It is the principal object of this invention to provide reinforced plaster board that will be relatively inexpensive to manufacture, 20 that is light in weight yet durable in use and which embodies reinforcing that will prevent the usual cracking or chipping off of the edges during transportation and handling and which further provides for 25 nailing it to a wall without chipping.

It is also an object of the invention to provide plaster board of the above character wherein the body portion is strengthened 30 by the embedding therein of woven wire netting and the edge portions are protected and also reinforced by the embedding therein of galvanized, sheet metal strips of angular form in cross section and slotted for 35 the reception of nails whereby it may be secured in place.

A still further object resides in the provision 40 of reinforcing strips for the edges of plaster board sheets having upturned edge flanges embedded in the sheet for the purpose of adding rigidity and which further serves as a means to which the ends or edges of wires for reinforcing the body may be attached and held in place while the plastic 45 material is being molded.

In accomplishing these and other objects of the invention, I have provided the improved details of construction, the preferred forms of which are illustrated in the accompanying drawings, wherein—

Figure 1 is a side view of a plaster board embodied by the present invention; a part of which is broken away to better illustrate the reinforcing thereof.

Figure 2 is an enlarged sectional view of the edge portion of a board, showing the re-

inforcing strip and attachment of the wire netting thereto.

Figure 3 is a similar view showing a modified construction for lap joints. 60

Figure 4 is a perspective view of a part of a reinforcing strip.

Referring more in detail to the drawings—

1 designates, in its entirety, a plaster 65 board embodied by the present invention. Such boards may be made in various widths and lengths convenient for use and from any suitable plastic composition such, for example, as a mixture of plaster and fibrous 70 material.

The present board, or sheet, is reinforced throughout its body portion by a strip of woven wire netting, designated at 2, which is embedded centrally between the opposite 75 side faces of the board. Along its longitudinal edges, the board is reinforced by the embedding therein of strips 3, preferably of galvanized sheet metal, as best shown in Figure 2. The netting 2 is supplemented by 80 heavy wires 4 extended lengthwise of the board in spaced apart relation.

The principal feature of the present invention resides in the form and disposition of the reinforcing strips 3. These in the 85 preferred form are of channel form in cross section, with a relatively wide base portion 5 that lies flush with one face of the board along the edge thereof, an outer edge flange 6 turned up along the edge of the 90 board and an inner edge flange 7 that is embedded in the board. The base portion 5 is provided at desirable intervals with longitudinally extending slots 8 through which nails 9, or the like, may be driven to 95 secure the board to a wall. Such reinforcing strips make possible the nailing of the boards securely and permanently in place without danger of chipping or cracking along the edges. 100

In the making of such boards, the binding strips 3 are first arranged along the opposite side edges of a mold, a layer of plastic material is spread in the mold, the strip of wire netting is then laid thereon and 105 it is of such width that its edges will overlap the binding strips 3 and the wire ends, as designated at 10, are bent laterally to hook over the flanges 7 to thereby hold the netting in place while the board is being 110 molded. This method of construction also adds strength to the board and prevents de-

tachment of the binding strips after the material has set. After so attaching the ends 10 to the strips, the final layer of plastic material is added and the board allowed to 5 set.

Where it is desired to construct the edges of the boards for lap joints, as shown in Figure 3, strips 3 of angle form in cross section are used, and in forming the slots 8, 10 the material is struck inwardly to form the flanges 14 to which the wire netting may be attached by hooking the ends 10 thereover.

Having thus described my invention, what I claim as new therein and desire to secure 15 by Letters-Patent, is:

1. A plaster board comprising a body of plastic composition, a rigid reinforcing strips of channel form, embedded therein along its edges having a slot for the reception of 20 anchor nails; said strips comprising relatively wide base flanges lying flush with a face of the board with a laterally turned flange at one edge overlapping the edge of the board and a laterally turned flange at 25 its other edge embedded within the board.
2. A plaster board comprising a body of plastic composition, a rigid channel form reinforcing strip embedded therein along its edge; said strip comprising a relatively wide base flange lying flush with a 30 face of the board and a laterally turned flange at its inner edge embedded within the

board and a laterally turned flange at its other edge overlapping the edge of the board, and a strip of woven wire netting embedded 35 in the board to reinforce its body portion and having the wires along the edge thereof hooked over the laterally turned flange of the inner edge of said reinforcing strip.

3. A lap joint connection for plaster 40 boards in combination having a tongue and groove formed respectively along their opposite edges, reinforcing strips embedded in the edges of the boards with slots therein adapted to register when assembled for 45 the reception of nails, or the like.

4. A plaster board comprising a body of plastic composition, rigid angular reinforcing strips embedded therein along its edges; 50 said strips each comprising a relatively wide base flange lying flush with a face of the board and provided with inwardly struck portions forming anchor flanges and leaving slots for the reception of anchor nails, or the like, and an inwardly turned flange 55 along the outer edge of the base flange overlapping the edge of the board, and a strip of wire netting embedded in the board to reinforce its body portion and having the wire ends along its edge hooked over the inwardly struck flanges of said strips.

Signed at Seattle, King County, Washington, this 3rd day of July, 1924.

BENJAMIN WOODHOUSE.
